ABSTRACT OF THE DISCLOSURE

A pumping device comprising a chamber from which gases are to be removed, a collector surface disposed in said chamber for receiving gases, the gases being chemically combined with said surface to provide a reaction product thereon, and means for removing the reaction product, thereby permitting additional reaction product to form. In a preferred embodiment of the present invention, a wire-like brush is utilized to remove the reaction product.

BACKGROUND OF THE INVENTION*Field of the invention*

The present invention relates generally to pumping devices, and more particularly to pumping devices which may be used to eliminate gases in a high-vacuum system. A high-vacuum system is one which is maintained at, say, from 10^{-2} torr to 10^{-8} torr. The pump of the present invention is not intended for use in pressures greater than 10^{-2} torr.

Description of the prior art

Several different types of pumping devices which are intended to maintain or improve the vacuum in a high-vacuum system have been developed in the past several years. Probably, the most common of these types is a diffusion pump. The operation of ordinary mercury or oil diffusion pumps consists of heating the pumping fluid until a sufficient quantity of vapor is obtained. This vapor rises to the top of the reservoir and into a jet assembly. Upon flowing out of the jet assembly, the pump fluid molecules entrap molecules of the gas to be pumped and force them into a region where they can be removed by a forepump. The cycle is repeated continuously until almost all of the vapor is removed. One of the main disadvantages of such a diffusion-type pumping system is that the process necessarily involves the use of vapors which are in some instances undesirable. Where an oil-type diffusion pump is used, the pump is a source of organic vapors which will coat the walls of the vacuum chamber and any parts therein. Mercury-type diffusion pumps require elaborate liquid air-cooled traps to prevent mercury vapor from entering the system to be evacuated.

Another type of vacuum pump is generally referred to as an ion pump. In this type of pump, there is generally located within the evacuating envelope an electron source and at least one ion collector element. The electrons are oscillated in the path of gas molecules moving within the envelope, the gas molecules being bombarded by the electrons. This electron bombardment results in ionization of the molecules, which ions are attracted to a cathode in which they are embedded. Further burial is accomplished by sputtering from the cathode to produce finely divided metal which aids the vacuum process through chemical reaction, absorption, and burial. Titanium is generally selected as a suitable metal for this application by reason of its relatively high chemical activity, especially insofar as the more usual gases (vapors) are concerned, and by reason of the stability of the majority of the titanium compounds in the solid form thereof.

2

at ordinary temperature. It will be apparent, therefore, that an ion pump requires a complicated structure comprising an electron source, means for oscillating the electrons and a cathode.

In still another type of pump, titanium is continually deposited on collector surfaces to react chemically with vapors in the region thereof. Some disadvantages of such a system, which usually operates on the principle of sublimation of titanium from a filament or anode onto the adjacent casing walls, are the temperatures required for titanium sublimation, the limited amount of titanium that can be deposited without recharging the source, and the fact that the casing walls must be maintained at room temperature or below in order to achieve a high gettering rate. Thus, the high temperature of the source and the low temperature of the walls represent conflicting conditions.

SUMMARY OF THE INVENTION

The pumping device of the present invention comprises a pump chamber or envelope from which gases are to be removed, the pump chamber or envelope being in communication with a main vacuum chamber. Thus, by evacuating the pump chamber, the main chamber is evacuated. Of course, the main chamber is evacuated to pressures of, say, 10^{-2} torr by conventional pumping means capable of achieving such pressures. The pump chamber is constructed with a suitable surface for receiving gases, the gases being chemically combined with the collector surface to provide a reaction product thereon. As the gases combine with the collector surface, the pressure in the pump chamber necessarily decreases and, consequently, additional gases move from the main chamber to the pump chamber. By providing means for continually removing the reaction product from the collector surface, these additional gases will continue to combine chemically with the fresh collector surface.

In a preferred embodiment of the present invention, the pump chamber is cylindrically-shaped and the collector surface comprises a cylindrical wall of titanium which is concentrically mounted in the pump chamber. The collector surface may be the inner wall of the pump chamber. A wire brush is engaged with the inside surface of the titanium wall, the brush being effective, when moved while engaged with the inside surface, to remove the reaction product therefrom so that additional reaction product may form.

Thus, it will be apparent that the pumping device of the present invention does not suffer from the aforementioned disadvantages, i.e., the titanium does not have to be heated; the titanium wall may be made arbitrarily thick so the supply of titanium, for all practical purposes, is limitless; undesirable oil or mercury vapors are not involved; and a complicated structure is not required. In fact, a simple rotating shaft mechanism or the like for moving the wire brush is all that is required.

It is an object of the present invention, therefore, to provide a pumping device which does not utilize contaminating vapors or high temperatures to pump gases.

Another object of the present invention is to provide a pumping device for a high-vacuum system, which device comprises a collector surface for receiving gases, the gases being chemically combined with the collector surface to form a reaction product thereon, and a means for removing the reaction product so more reaction product can be formed.

Still another object of the present invention is to provide such a device wherein the means for removing the reaction product comprises a wire brush or suitable scraper which is engaged with the collector surface and means for moving the wire brush while it is engaged with the collector surface.

BRIEF DESCRIPTION OF THE DRAWINGS

The above-mentioned and other features and objects of this invention and the manner of attaining them will become more apparent and the invention itself will be best understood by reference to the following description of an embodiment of the invention taken in conjunction with the following drawings wherein:

FIG. 1 is a vertical sectional view of a preferred embodiment of the present invention showing a cylindrical titanium wall, a wire brush engaged with the wall and means for moving the brush relative to the wall;

FIG. 2 is a cross-sectional view taken from FIG. 1 generally along the line 2—2;

FIG. 3 is a fragmentary, axial section of another embodiment of this invention; and

FIG. 4 is a cross-section taken substantially on section line 4—4 of FIG. 3.

DESCRIPTION OF PREFERRED EMBODIMENTS

Referring now to the drawings, it will be seen that the pumping device, indicated generally by reference number 10, comprises a cylindrically-shaped housing having a cylindrical, outer wall 12, an upper end plate 14 and a lower end plate 16, the housing, therefore, defining a chamber from which vapors are to be removed. The upper end plate 14, which is welded to the upper edge of the cylindrical wall 12, as indicated by reference number 18, is provided with a centrally-located opening 20 in which a cylindrical pipe 22 is disposed. Of course, the pipe 22 is welded or otherwise securely joined to the end plate 14 so that gases cannot enter the pump 10 except through the pipe 22. For instance, pipe 22, which preferably has an outer diameter substantially equal to the internal diameter of the hole 20, may be welded to the end plate 14 as indicated by reference number 24.

The end plate 16 is welded to the cylindrical wall 12 as indicated by reference number 26 so gas cannot enter the pump 10 through the joint between the cylindrical wall 12 and the end plate 16. An inverted, generally bell-shaped housing 28, fragmentarily shown in FIG. 1, is mounted on the underneath side of the end plate 16 by means such as screws 30 which extend through holes 34 in a horizontal flange 32 of the housing 28 and which are threaded into the end plate 16. A conventional O-ring or copper gasket seal 36 is provided between the underneath side of the end plate 16 and the flange 32 of the housing 28.

In recapitulation, it can be seen that the cylindrical wall 12, end plate 14, end plate 16 and housing 28 define a chamber having an input port (pipe 22) and no exhaust ports. Thus, gas entering the pumping device 10 must enter through pipe 22. The pipe 22, therefore, will be connected to a vacuum chamber, not shown, which is to be evacuated. As stated previously, the vacuum chamber, to which pipe 22 is connected, will be preliminarily evacuated down to 10^{-2} torr or less before pump 10 will be energized.

A shaft 38 is journaled in the pump 10, the axis of the shaft 38 being substantially coincident with the axis of the cylindrical wall 12. Specifically, the shaft 38 is supported on at least one thrust bearing, such as thrust bearing 40 in FIG. 1 which is shown supported on a bearing mount 42 which, in turn, is supported on a shoulder 44 in the housing 28. A pair of snap rings 46 is disposed in spaced-apart grooves 48 in the shaft 38 to retain the inner race of bearing 40 against axial movement on the shaft 38.

Rigidly mounted on the lower end of shaft 38 and within the housing 28 is a cylindrically-shaped iron block 50, the axis of block 50 preferably coinciding with the axis of shaft 38. A rotatable magnet 52, fragmentarily shown in FIG. 1, is disposed outside housing 28, the magnet 52 being journaled for rotation about the axis of shaft 38. When the magnet 52 is rotated, block 50 is rotated, and, since block 50 is rigidly mounted on shaft

38, shaft 38 is rotated. Thus, the rotatable magnet and iron block 50 comprise means for driving shaft 38, the driving means being arranged so shaft 38 can be rotated without breaking the seal of the pumping device 10 chamber. Such means for driving a shaft are well known and need not be discussed in detail in this description.

The pumping device 10 is not limited to the driving means illustrated in FIG. 1 and several other types of driving means may be developed and used by those persons skilled in the art, the only requirement being that rotation of the shaft 38 does not permit vapors and gases to enter the pumping device 10 chamber.

The pumping device 10 further comprises an inner wall 56 which in the illustrative embodiment is a cylindrical wall having an outer diameter substantially equal to the inner diameter of the cylindrical wall 12. Referring to FIG. 1, it will be seen that end plate 14 is provided with a circumferentially extending notch 58 for receiving the upper edge portion 60 of the inner wall 56 and that the lower edge portion 62 of the inner wall 56 is held outwardly against cylindrical wall 12 by a ring 64. Ring 64 is held in a selected vertical position by means such as the crew 66 shown in FIG. 1.

An axially extending brush or scraper, indicated generally by reference number 68, is engaged with the inside surface of the inner wall 56, the brush 68 comprising a rigid holder 70 and a scraper portion 72 which may be constructed of stiff, wire-like material. The scraper portion 72 may also be a single flexible blade or blades arranged to engage and scrape the inside surface of inner wall 56.

As seen in FIG. 1, means are provided for drivingly connecting holder 70 to shaft 38 so that, when the shaft is rotated, scraper portion 72 is moved about the inside surface of inner wall 56. Specifically, an adapter 74 is mounted on the upper end of shaft 38 and held against rotation relative to the shaft by means of screws 76. A pair of links 78 is provided for connecting holder portion 70 to the adapter 74, each of the links 78 being pivotally connected to the holder portion 70 as indicated at 80 and pivotally connected to adapter 74 by one of the screws 76. Thus, when the pivot point 80 moves about the axis of screws 76 in the direction of arrow 82, holder 70 is moved radially outwardly toward the inside surface of inner wall 56. A horizontally disposed ring 84 is slidably carried on adapter 74 as shown in FIG. 1. A collar 86 is arranged to fit over the upper end of shaft 38 and to rest on ring 84 which is held against downward movement by links 78. The collar 86 is provided with an axially extending hole 88 through which a screw 90 extends, the screw 90 being threadedly engaged with adapter 74 as indicated at 92. Thus, by tightening screw 90, the ring 84 is urged downwardly against links 78 to urge the scraper portion 72 into engagement with the inside surface of inner wall 56.

An annular cup 94 is mounted on shaft 38 by means such as the screw 96, the annular cup 94 being arranged to collect reaction product which is brushed or scraped from the inside surface of wall 56 and which falls downwardly toward cup 94. It will be seen that ring 64 acts as a shoulder or deflector causing the reaction product to fall into cup 94.

In a preferred embodiment of the present invention, inner wall 56 is fabricated from titanium and the balance of the parts which are exposed to the inside of the pumping device 10 except the iron block 50 are fabricated from stainless steel. Thus, in a preferred embodiment of the present invention, the brush 68 has stainless steel bristles engaging the inside surface of wall 56.

It will be apparent that the inner wall 56 may be removed from the pumping device 10 by removing housing 28, shaft 38 which carries brush 68, annular cup 94 and ring 64 which secures inner wall 56 to the outer wall 12. The inner wall 56 is therefore an easily replaceable element of the pumping device 10.

In operation, pumping device 10 receives gas molecules through the pipe 22, the gas molecules being collected on the inside surface of inner wall 56. Since, in a preferred embodiment, inner wall 56 is fabricated from a material such as titanium, the gas molecules combine chemically with the surface of inner wall 56 to form a reaction product, such as titanium oxide, thereon. After a period of time, the inside surface of inner wall 56 will be entirely covered with this reaction product and consequently the gas molecules cannot be gettered. This invention, therefore, provides means for continually removing the reaction product so additional reaction product can be formed. Obviously, the gas molecules which chemically combine with the inside surface of inner wall 56 are removed from the system and therefore the pressure in the system is decreased. Generally speaking, the pumping device 10 comprises means for providing, in a high-vacuum system, a large surface of reactive metal, such as titanium, which is continually scraped and cleaned so that gas molecules can be continually gettered thereby.

Titanium will readily combine with hydrogen, nitrogen, oxygen, carbon monoxide, carbon dioxide and water vapor. Of course, in some instances, barium may be used to provide a collector surface since barium will readily combine with oxygen and compounds thereof to form stable, low vapor pressure compounds.

It will be apparent that pumping device 10 is controllable in that the screw 90 can be adjusted to determine the pressure with which brush 68 is engaged with inner wall 56. Of course, a coiled, compression spring may be disposed between collar 86 and ring 84 to urge the ring 84 downwardly against the links 78, thereby resiliently engaging brush 68 with the inside surface of the inner wall 56.

The pumping device 10, as illustrated, is used in the vertical arrangement illustrated so that reaction product removed from the inside surface of wall 56 can fall down into the annular cup 94. For use in the horizontal position or any position therebetween, a slot in the cylinder can be provided to catch the reaction products.

It will be apparent that the pumping device of the present invention is not limited to the cylindrical arrangement shown in FIGS. 1 and 2 and that one skilled in the art, using the concepts of the present invention, could easily devise a system which would have a flat collector surface and some other means for moving the brush 68 against the flat surface.

Referring to FIGS. 3 and 4, a second embodiment of this invention will be described. Like numerals indicate like parts. In this embodiment, the cylindrical housing 12 has positioned thereinside a titanium cylinder 56a in spaced coaxial relationship. The titanium cylinder 56a is mounted on the housing 12 by a series of helical springs 96 circumferentially and axially spaced as shown. The springs 96 are under compression and are secured at the inner ends thereof to attachment rings 97 secured to the cylinder 56a. The opposite ends of the springs 96 are frictionally engaged with the housing 12 under a force dependent upon the degree of compression of the springs, the force being adequate to hold the titanium cylinder 56a in position. By means of this spring mounting, the titanium cylinder 56a is capable of being moved radially with respect to the housing 12.

Coaxially positioned inside the titanium cylinder 56a is the rotatable shaft 38 having mounted thereon a rigid brush holder 98. This brush holder 98 is formed of two flat pieces 104 and 106 abutted together and clamped to shaft 38 by means of suitable screws 100. A square cutout 102 formed between the two flat pieces firmly frictionally embraces the shaft 38 such that rotation of shaft 38 will result in rotation of the brush holder 98. The brush 72 is also clamped between the two flat pieces 104 and 106 and engages the inside surface of the titanium cylinder 56a the same as explained in connection with the preceding embodiment.

A guide ring 108 is secured to the housing 12 in coaxial relation therewith and extends radially inwardly to a position just beneath the titanium cylinder 56a as shown. The internal diameter of the ring 108 is about equal to that of the titanium cylinder 56a.

The upper end wall of chamber 12 as well as the ring support serve as end stops or guides for the titanium cylinder 56a in limiting vertical movement thereof. Preferably, the length of the titanium cylinder 56a is made only slightly smaller than the distance between the end wall and ring guide 108.

A residue cup 94 is secured to the shaft 38 for rotation therewith and is disposed immediately beneath the titanium cylinder 56a to catch the residue which falls from the inner surface of the titanium cylinder 56a.

Operation of this embodiment of FIGS. 3 and 4 is substantially identical to that of the arrangement of FIGS. 1 and 2. However, in the initial assembly, the bristles of the brush 72 are engaged forcefully with the inside surface of the titanium cylinder 56a, the bristles forming this brush 72 being sufficiently resilient to engage forcefully this surface. Thus, as the shaft 38 is rotated, the brush 72 will rotate and perform a scraping action against the cylinder surface. Inasmuch as the cylinder 56a is spring-mounted, it is free to flex radially. If there should be any eccentricities between the shaft 38 or the brush 72, these are automatically compensated for by reason of the radial movement of cylinder 56a. Additional advantages reside in the construction of the brush assembly and its mounting on the shaft 38 being simpler. Also, the spring mounting of cylinder 56a results in a decrease in vibration and noise.

A third embodiment is illustrated also in FIGS. 3 and 4 in the respect that the cylinder 56a may be provided with an axially extending slot 110 such that the pump may be operated on its side with the residue from the inside of the cylinder 56a falling therethrough as the brush 72 operates. For such operation, obviously the residue cup 94 would not be needed.

While there have been discussed above the principles of this invention in connection with specific apparatus, it is to be clearly understood that this description is made only by way of example and not as a limitation to the scope of the invention.

What is claimed is:

1. A pumping device comprising a cylindrically-shaped housing defining a chamber from which gases are to be removed, the inside surface of the cylindrical wall of said chamber being formed of a material which will chemically react with the gases to form a reaction product on said surface, and means for removing said reaction product from said surface, said removing means comprising elongated axially extending scraper means engageable with said inside surface and effective when moved while engaged with said surface to remove said reaction product, a shaft journaled for rotation inside said chamber, the axis of said shaft substantially coinciding with the axis of said chamber, means for drivingly connecting said scraper means to said shaft, and means for rotating said shaft.

2. A pumping device as in claim 1 wherein said material from which said inside surface is formed is titanium and wherein said scraper means includes wire-like bristles which are engaged with said surface.

3. A pumping device as in claim 1 wherein said means for drivingly connecting said scraper means to said shaft includes at least one link having one of its ends pivotally connected to said scraper means and the other of its ends pivotally connected to said shaft, said link extending radially outwardly from said shaft, and means for pivoting said link on said shaft to urge said scraper means into engagement with said surface.

4. A pumping device as in claim 1 further comprising an annular cup carried by said shaft and arranged to receive the reaction product removed from said surface,

the axes of said shaft and cylindrical wall being vertical.

5. A pumping device comprising a cylindrical housing defining a chamber from which gases are to be removed, a collector surface disposed inside said housing for receiving gases, the gases being chemically combined with said collector surface to form a reaction product thereon, means for removing said reaction product from said surface thereby permitting additional reaction product to form, said removing means comprising a scraper engaged with said surface and means for moving said scraper relative to said surface, said collector surface being the inner surface of a cylindrically shaped titanium wall, said wall being substantially coaxially positioned inside said housing, and means for resiliently mounting said titanium wall

10

inside said housing whereby said wall is capable of moving radially.

6. A pumping device as in claim 5 wherein said resilient mounting means includes a series of springs interposed between said wall and said housing.

7. A pumping device as in claim 5 wherein said titanium wall has an opening therein through which residue scraped off the surface thereof may fall.
